UNITED STATES PATENT OFFICE.

MILTON CLARK, OF BALTIMORE, MARYLAND, ASSIGNOR TO THE CONTINENTAL CASH CAR COMPANY OF BALTIMORE, OF SAME PLACE.

STORE-SERVICE SYSTEM.

SPECIFICATION forming part of Letters Patent No. 293,949, dated February 19, 1884.

Application filed January 23, 1884. (No model.)

To all whom it may concern.

Be it known that I, MILTON CLARK, of Baltimore, in the county of Baltimore and State of Maryland, have invented certain new and useful Improvements in Store-Service Systems; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates, particularly, to that class of store-service systems in which from a central station or cashier's desk track-wires radiate in various directions to the several salesmen's counters, the carriers depending from overhead wheel supports or cars adapted to travel by gravity to and from the central station, according as the outer end of the track-wire is raised above or lowered beneath a horizontal plane. The velocity of movement of the car in each case is necessarily dependent upon the angle of inclination of the track to this plane. The outer stations or salesmen's counters being, however, at varying distances from the cashier's desk, it is evident that to produce uniformity of speed throughout the entire system, insuring like inclination for each track and equal velocity of movement for all the cars, it is needful that means should be provided, in connection with each track, for bringing the several wires with certainty into the proper plane of inclination. These means should, moreover, be as far as possible under the immediate supervision and control of the cashier, and should not be left to the carelessness or inefficiency of the general force of salesmen. It is desirable, therefore, that the inner or fixed ends of the system at the central station should be readily adjustable in different horizontal planes, according to and corresponding with the distances of the outer or movable ends from such central station, so that in the event of a desired shifting of the outer end of any one of the wires from a distant salesmen's counter to one nearer the cashier's desk, or vice versa, the proper grade or inclination may be at once established by proper vertical adjust-

ment of the fixed end. My present invention is adapted to secure these desirable results, and by it I am also enabled to stretch or tighten sagging wires with ease and celerity. At 55 the salesmen's stations I also provide appropriate safeguards against reckless operation of the gravity-switch, whereby injurious jars and strains beyond the normal wear and tear upon its constituent parts are avoided and the 60 occasion for repairs materially lessened.

Referring more particularly to the accompanying drawings, in which like letters indicate like parts, Figure 1, Sheet 1, represents in side elevation a single wire of my system 65 extending from the cashier's desk to one of the salesmen's counters. Fig. 2, Sheet 2, represents in side elevation an enlarged view of a salesman's station, showing more clearly the details of the gravity-switch. Fig. 7, Sheet 70 2, represents a detail of the same. Figs. 3, 4, and 5, Sheet 3, represent in front, top, and side elevation, respectively, the means of adjustment at the cashier's desk. Fig. 6, Sheet 3, represents a detail of the same. Fig. 8, 75 Sheet 4, represents the system in plan. Figs. 9 and 10, Sheet 5, represent in side elevation modifications of the arrangement of devices at the salesman's station. Figs. 11 and 12, Sheet 5, represent in top and side elevation 80 (the latter partly in section) a modification of the central or cashier's adjusting-plate.

A represents the cashier's desk, and H H' H'', &c., the various wires leading to salesmen's counters at varying distances therefrom, B B' B'', &c.

F is a car in transit upon one of the wires, and G G spring-retaining stops or buffers at the ends of the line.

E represents the salesman's shelves, in front 90 of which is arranged the gravity-switch, secured thereto in the ordinary manner by brackets x y, sustaining the vertical guide-rod T and the fixed pulley W.

In prior devices embodying these generic 95 features it has been usual to connect the end of the wire H with a sliding piece traveling upon the guide-rod by means of grooved rollers. I may substitute for this sliding piece the concentric sleeve U, (shown in Fig. 2,) 100 having a front lug for attachment of the wire and side bails for the operating-cord Q. In-

stead of hanging cords terminating in hand-pulls, generally employed for raising and lowering the slide, I may substitute the endless cord Q and winding-drum R. By this construction the salesman is prevented from operating the slide with such rapidity as to cause it to strike violently against the bracket X and sleeve W, which has been the occasion of much annoyance and expense with the hand-pull hangers. The operation of turning the winch of the winding-drum necessarily involves a gradual ascent and descent of the slide, which reaches its upper and lower limits without perceptible shock or jar.

At the cashier's desk, and preferably suspended from the ceiling by a sustaining shoulder-post, D, are situated the two pairs of guide-rails M N. These may have, as represented in the drawings, an upward curvature, or, in some instances, may be straight and parallel throughout. The post D passes between the pairs of rails, and has an upper fixed collar, b, and screw-nuts c and d, clamping the rails firmly upon the post. The rails are thus held apart a distance equal to the diameter of the post, leaving a longitudinal passage between each pair, the two being separated also by an intervening space equal to the distance between the screw-nuts. In the longitudinal grooves are situated the sliding bolts I, extending through the grooves and passing through the angled guide-plates J, to which they are secured by bolt-heads and retaining-nuts. One or more lock-nuts f f serve to secure the bolts in any position along the length of the rails. Upon the bolts are situated the adjustable sleeves L, provided with binding-screws S, and forward right-angled extension-arms K, carrying the transverse bolts P. This bolt is provided with a retaining-nut, m, lock-nut n, and head r, adapted for the reception of a turning key or wrench. The track-wires H H' H'', &c., are attached to these bolts in any suitable manner—for instance, as represented in Fig. 6—by passing the end of the wire through a perforation in the bolt and forming such end into a loop or knot. In some cases, however, I contemplate dispensing entirely with the sleeve-pieces L, attaching the wires directly to the vertical bolt I, and at any desired height upon said bolts. This arrangement I may adopt either when the rails are upwardly curved or when they are arranged, as they may be, in a horizontal, vertical, or diagonal position.

From the description of parts the mode of operation of my device is apparent. When it is desired to change the grade of any of the tracks, the sliding sleeve L may be moved up along the bolt I. This will suffice for small changes in the inclination of the tracks. If the sleeves are not used, the wires may be secured directly to the bolts and at the desired height. Greater changes in the inclination of the wires are obtained by loosening the lock-nuts of the bolts and moving the latter along

the guides to a higher or lower horizontal plane, as the case may be. The slack of the wires, occasioned by sagging, may be taken up by loosening the lock-nut n and revolving the transverse bolt P by a wrench or key engaging with the bolt-head r, or otherwise.

In Figs. 9 and 10 I have illustrated modifications of my gravity-switch. In both these cases the pulleys W are situated upon the summit of the upright standards T, thus giving a greater play to the carriage Z, running on wheels t t'. In Fig. 9 the rope is operated by the hand-pulls T' T'', and in Fig. 10 by the winding-drum R. In place of the carriage, Fig. 9, may be substituted the sleeve-piece U of Fig. 2, which may be in like manner operated by hand-pulls T' T''.

Figs. 11 and 12 illustrate a horizontal center plate, which may be used at the cashier's desk in place of that shown on Sheets 1 and 2. The wires H H' H'', &c., lead to the various salesmen's counters, and are attached to upright bolts I, playing in grooves in the plate, and secured in position by the heads r r', &c., and lower nuts, z z', &c. Locking-nuts f f serve to secure the bolts at any desired point. The wires may also be attached at any point up or down along the height of the bolts, as shown in Fig. 12. The center plate is preferably made of two pairs of rails joined or hooped at their ends, and united by transverse cross-ties t t', &c. It may consist, however, of merely a lower plate grooved and provided with upright headed bolts projecting above the plate, said bolts being secured in the groove and at their lower ends by locking and retaining nuts. The heads on the bolts in either case are shaped for engagement with a turning key or wrench for tightening the wires.

It is evident that some form of sliding piece other than the carriage or sleeve may be employed in connection with my upright standard, rope, and winding-drum or handles. In my seventeenth claim, therefore, I use the word "sliding-piece" generically to cover all such forms.

Having thus described my invention, what I claim, and desire to secure by Letters Patent, is—

1. A store-service system consisting of a series of wires radiating from a central or cashier's station to various salesmen's counters or sub-stations, and provided with means at the central station for varying the grade of any or all of said wires, substantially as described.

2. A store-service system consisting of a series of wires radiating from a central or cashier's station to various salesmen's counters or sub-stations, and provided with means for moving any or all the ends of the wires at the central station to different elevations or horizontal planes, substantially as described.

3. A store-service system consisting of a series of wires radiating from a central or cashier's station to various salesmen's counters or sub-stations, and provided with means for

moving the ends of the wires to the right or left of the vertical planes in which they are originally placed, substantially as described.

4. A store-service system consisting of a se-

ries of wires radiating from a central station to various salesmen's counters or sub-stations, and provided with means for tightening or stretching each of the said wires.

5. In a store-service system, a central fixture provided with horizontally-movable attachments for the inner ends of the wires, substantially as described.

6. In a store-service system, a central fixture provided with vertically-adjustable attachments for the inner ends of the wires, substantially as described.

7. In a store-service system, a central fixture provided with horizontally and vertically adjustable attachment for the inner ends of the wires, substantially as described.

8. In a store-service system, a central fixture composed of guide-rails and connecting-bolts, substantially as described.

9. In a store-service system, the combination of guide-rails M N, having a central opening, with the adjustable bolts I I, provided with means for locking them in any position upon said rails, substantially as described.

10. In a store-service system, the guide-rails M N, having an upward curvature, in combination with the adjustable locking-bolts I I, substantially as described.

11. In a store-service system, the adjustable bolts I I, in combination with sleeve-clamps 35 L, having means for attaching thereto the wire H, substantially as described.

12. In a store-service system, the bolts I I, in combination with sleeve-clamps L, having extended arms K K and transverse bar P, provided with key-head r, and lock-nut n, substantially as described.

13. In a store-service system, the combination of a wireway, adapted to be raised and

lowered at the salesman's end with upright standard T, sleeve-piece U, having lugs or 45 bails V V, rope Q, and drum R, substantially as described.

14. In a store-service system, the combination of a wireway, adapted to be raised and lowered at the salesman's end, with upright 50 standard T, sleeve U, having lugs or bails V V, rope Q, and handles T' T'', substantially as described.

15. In a store-service system, the combination of a wireway, adapted to be raised and 55 lowered at the salesman's end, with upright standard T, carriage Z, with wheels l l, rope Q, and drum R, substantially as described.

16. In a store-service system, the combination of a wireway, adapted to be raised and 60 lowered at the salesman's end, with upright standard T, carriage Z, with wheels l l, rope Q, and handles T' T'', substantially as described.

17. In a stove-service system, the combination of a wireway, adapted to be raised and 65 lowered at the salesman's counter, with an upright standard, a piece sliding thereon, to which the end of the way is attached, a rope, and winding-drum, substantially as described.

18. In a store-service system, a center plate 70 at the cashier's desk, flat or horizontal throughout, and provided with a series of tightening-bolts, substantially as described.

19. In a store-service system, a center plate 75 at the cashier's desk, flat or horizontal throughout, and provided with a series of tightening-bolts adjustable in the grooves of said plate, substantially as described.

In testimony that I claim the foregoing as my own I affix my signature in presence of two 80 witnesses.

MILTON CLARK.
